Duane L. Ripley, Buffalo, N. Y., assignor to Markel
Electric Products, Inc., Buffalo, N. Y., a corpo-
ration of New York

Application April 11, 1938, Serial No. 76,431

Term of patent 14 years

To all whom it may concern:

Be it known that I, Duane L. Ripley, a citizen
of the United States, residing at Buffalo, in the
county of Erie and State of New York, have in-
vented a new, original, and ornamental Design
for a Diffuser for Electric Lighting Fixtures, of
which the following is a specification, reference
being had to the accompanying drawing, form-
ing a part thereof.

In said drawing:

Figure 1 is a side view of a diffuser for electric
lighting fixtures embodying my new design.

Figure 2 is a bottom plan view of the diffuser.

I claim:

The ornamental design for a diffuser for elec-
tric lighting fixtures, substantially as shown.

DUANE L. RIPLEY.
